RECOIL MECHANISM

Joseph Tannenbaum, Detroit, Mich., assignor to the United States of America as represented by the Secretary of the Army

Filed May 2, 1957, Ser. No. 656,732

7 Claims. (Cl. 89—43)

(Granted under Title 35, U.S. Code (1952), sec. 266)

The invention described herein may be manufactured and used by or for the Government for governmental purposes without the payment of any royalty thereon.

The invention relates to recoil mechanism for ordnance and especially relates to mechanisms which employ fluids to absorb and redistribute the recoil forces.

In the manufacture of armored tanks and self-propelled gun vehicles space restrictions are very important as the limited space available must be used most efficiently. As the operating mechanism of the gun is located within the interior of the tank or other vehicle, the size of these mechanisms must be kept to a minimum, yet must be strong enough to withstand the large recoil forces produced when the gun is fired. The invention contemplates a most efficient use of space to house the recoil mechanism, yet meet the necessary strength requirements.

In prior gun recoil mechanism it has been common to integrate the recoil, counter recoil, and often the counter recoil buffering mechanism into a single fluid unit. This construction is susceptible to mechanical failure upon air leaking into the fluid system in that the air will affect all three stages of the recoil. Also, the use of an integrated recoil system necessitates a complete dismantling of the entire mechanism if the structure of any one of the three stages needs repair or a replacement of parts. The invention contemplates a design in which the fluid systems of the recoil, counter recoil and counter recoil buffering mechanisms are separate and a failure in one stage will not affect the other stages, likewise one stage may be disassembled for repair without disturbing the mechanism of the other recoil stages.

It is therefore an object of the invention to produce a recoil mechanism which is compact and conforms closely to the contours of the gun breeching mechanism thereby occupying a minimum of space.

Another object of the invention is to design a recoil mechanism that is light weight and of a simple construction.

A further object of the invention is to construct a recoil mechanism in which the recoil, counter recoil and counter recoil buffering units are fluid operated, each unit having an individual oil reserve and capable of being serviced independently.

Yet another object of the invention is to design a gun recoil mechanism in which the recoil, counter recoil and counter recoil buffering units are distinct mechanisms and may be spatially arranged at the discretion of the gun designer.

Fig. 1 is a cross-sectional elevation of one embodiment of the invention.

Fig. 2 is an end view of the Fig. 1 from the right.

Fig. 3 is a cross-sectional elevation of the counter recoil assembly.

Fig. 4 is a cross-sectional elevation of the buffering assembly.

Fig. 5 is a cross-sectional elevation of another embodiment of the invention.

Fig. 6 is an end view from the right of a gun breech incorporating the embodiment of Fig. 5.

Fig. 7 is a fragmentary cross sectional elevation view taken along the line 7—7 of Fig. 2 of the embodiment of the invention shown in Fig. 1.

As shown in Fig. 1, an embodiment of the invention comprises a gun 10 generally consisting of a barrel 12 supported by a cradle 14. A breech ring 16 is attached to the barrel 12 such that when the gun is fired the barrel 12 and breech ring 16 will move backward under recoil, guided by cradle 14. Concentric with the barrel 12 and attached to the breech ring 16 is a recoil piston 18. Recoil piston 18 therefore will slide within cradle 14 and is supported by bearing 20 and bearing surface 22 of the cradle 14. An annular flange 24 is formed on the exterior surface of piston 18 and extends into a tapered cylinder 26 of the cradle 14. A floating seal 28 is slidably interposed between the wall of cylinder 26 and recoil piston 18 and prevents the hydraulic fluid which fills cylinder 26 from escaping. It will be noted that the flange 24 does not touch the wall of cylinder 26 but leaves a clearance whereby during recoil the fluid may flow over flange 24 as the flange and piston 18 move rearwardly. The cylinder 26 is tapered converging towards the breech ring thereby increasing the resistance of the fluid flow over flange 24 as the piston 18 moves during recoil. As bearings 20 and 22 support the weight of the piston 18 and barrel 12, seal 28 will not be subjected to any appreciable weight and will provide an effective seal for a long period of time.

A reservoir 30 may be connected to cylinder 26 by means of conduit 32 and passageway 33 to supplement any lost fluid.

As the gun 10 moves back to battery position, the fluid again flows to the rear of flange 24 and is ready to absorb the shock of the next recoil.

The gun 10 is moved back to the battery position by the counter recoil mechanism which consists of cylinders 34 fixed by bolts or such to the cradle 14. A piston 35 and piston rod 36 operate within cylinders 34, the outer end of which is connected to extension 38 of breech ring 16. It will be seen therefore that as the gun recoils, extension 38 will move piston rod 36 rearwardly tending to compress the fluid in cylinders 34.

A recuperator 40 is bolted to the cradle as seen in Fig. 1. The recuperator consists of a cylinder housing 42, the ends of which are sealed by means of caps 44. A piston 50 is slidably positioned in housing 42 and is biased in one direction by means of springs 46. A conduit 49 connects the rear of cylinder 34 with opening 48 in the housing 42 permitting hydraulic fluid to flow from the cylinders 34 to the housing 42 when the breech ring 16, extension 38 and piston rod 36 move rearwardly during recoil. During this compression stroke, the fluid will force piston 50 into housing 42 compressing springs 46.

After the recoil movement has terminated, the force exerted on the fluid in the counter recoil cylinders 34 by springs 46 will move the gun back into a battery position. A fitting 52 is attached to upper cap 44 for replenishing the fluid in housing 42.

Considerable kinetic energy is developed in the forward travel of the gun under the pressure generated by springs 46 and means are provided to bring the gun to rest in the battery position with a minimum of shock.

The counter recoil buffering means comprises cylinders 54 which are fixed to the cradle 14 by bolts or such. A piston rod 56 reciprocates within cylinder 54 on which is attached a piston 58. The diameter of piston 58 is slightly less than the internal diameter of cylinder 54 allowing the fluid in cylinder 54 to slowly flow from one side of piston 58 to the other. A spring 60 biases

the piston 58 and piston rod 56 toward the breech ring 16.

As the gun 10 and breech ring 16 move back into battery, the abutment end 62 of piston rod 56 which is normally in abutting relation with breech ring 16 prior to firing of the gun, will contact the breech ring 16, and the resistance of the fluid flow from one side of piston 58 to the other will cushion the return movement.

The operation of the device is as follows:

As the gun recoils, the rearward movement of the breech ring 16 moves recoil piston 18 to the right as viewed in Fig. 1. Hydraulic fluid within tapered cylinder 26 flows over flange 24 with increasing resistance thereby absorbing the recoil movement. As the breech ring 16 moves rearwardly, the piston 35 and piston rods 36 of the counter recoil cylinders 34 will also be moving in the same direction thereby circulating the fluid in cylinders 34 through conduit 49 and opening 48 to compress springs 46. After the recoil movement is completed, the fluid pressure created by springs 46 returns the gun to battery through forces exerted in cylinders 34. Prior to the gun reaching battery position, the breech ring 16 will engage the abutment 62 of the counter recoil buffering piston rod 56 thereby cushioning the return movement of the gun 10.

It will be observed that each of the units is self-contained and each has its own fluid reservoir, therefore a failure of the counter recoil mechanism, for instance, will not affect the recoil components or vice versa.

Should one of the units need repair or adjustment, there is no need to disturb the other units, as each may be serviced independently, which permits rapid repair as is desired under battle conditions.

A modification recoil mechanism is shown in Fig. 5 wherein cylinders 64 are fixed to the cradle 14' by suitable means. As a plurality of similar cylinders 64 are used, only one will be described, wherein breech ring 16' supports a piston 66 which is of a tubular configuration and mounts a flange 68 at the end. The internal wall of cylinder 64 is tapered toward breech ring 16' and hydraulic fluid fills the space between piston 66 and the wall of cylinder 64 such that during recoil the piston 66 will be pulled rearwardly by the breech ring 16' and the flow of fluid over flange 68 will cushion the recoil movement as described in the above embodiment.

A cylinder 70 is supported at one end by cylinder 64 and is concentric thereto. A cap 72 seals the above mentioned end of cylinder 70 and provides the supporting means therefor.

A piston 74 is also mounted in breech ring 16', concentric with piston 66 and extends through the unsupported end of cylinder 70. A plunger 76 is formed on piston 74 and an axial bore 78 intersects bore 80 forming a fluid connection between the space defined by piston 74, the inner wall of cylinder 70 and chamber 82 of the breech ring 16'.

A pair of cylinders 84 are mounted on the breech ring 16' for movement therewith. Cylinders 84 are in effect a nitrogen recuperator and consists of a floating piston 86 and an end plug 88 which encloses a chamber 90 which is filled with a compressible gas such as nitrogen.

Chambers 82 are connected to each other by means of conduit 92 formed in the breech ring 16' and a conduit 94 provides a fluid connection from one of the chambers 82 to the cylinder 84 and piston 86.

Counter recoil buffering cylinders 54, such as disclosed in the first embodiment, may be used with this modification and operate in the above described manner.

The operation is as follows:

During recoil, the flow of fluid over flange 68 absorbs the recoil force as the breech ring 16' moves rearwardly. During this movement, piston 74 will also be drawn to the rear forcing the fluid within cylinder 70 into bores 80 and 78. This causes fluid to be transferred through chambers 82 to the cylinder 84 forcing piston 86 to com-

press the gas in chamber 90. At the end of the recoil motion the gas pressure will cause the fluid flow to reverse and return the gun 10 to battery. The counter recoil buffer cylinders 54 will absorb the kinetic energy created in the return movement.

This embodiment of recoil mechanism may be readily adapted to a large variety of guns. Any number of recoil cylinders 64 or gas cylinders 84 may be used depending on the requirements. Buffer cylinders 54 likewise may be located at the designer's discretion for most effective use. Here again it will be noted that the recoil, counter recoil and buffer units each have a separate fluid system, therefore eliminating a compounding of malfunction should air get into the fluid or leakage occur as would be the case in those systems where a single fluid system is used to operate all of the recoil mechanism units or components.

It is therefore seen that the present invention discloses a recoil mechanism which is compact, lightweight, dependable and may be arranged spacially at the discretion of the designer. Repairs and adjustments may be made quickly to one unit without disturbing other units, and a failure of one phase of the recoil mechanism will not affect the performance of the other phases.

Although the invention has been particularly shown and described in two modifications, it will be understood that the invention is capable of further modification and that changes in the construction may be made without departing from the spirit or scope of the invention as expressed in the following claims.

I claim:

1. Gun barrel recoil movement responsive mechanism for absorbing barrel recoil and for returning said barrel to battery position on a gun with a fixed cradle and a movable barrel with breech ring slidably mounted in said cradle; said mechanism comprising, in combination, a barrel recoil movement absorbing fluid system including a recoil cylinder formed within said cradle concentric with said barrel, a movable tubular recoil piston in and concentric with said recoil cylinder and attached to said breech ring for recoil and counter recoil actuated movement therewith, a barrel flange on said recoil piston extending into and of a diameter less than said recoil cylinder to permit restricted fluid flow therein, and a recoil force absorbing fluid within said recoil cylinder, a barrel counter recoil movement providing fluid system fluidly independent of said barrel recoil movement absorbing fluid system and including a counter recoil cylinder fixed to said cradle, a movable counter recoil piston within said counter recoil cylinder and actuatable attached to said breech ring for actuating counter recoil movement of said breech ring upon termination of barrel recoil movement, said counter recoil piston movably cooperating with said barrel recoil piston during barrel recoil to absorb barrel recoil forces, a recuperator having a recuperator cylinder fixed to said cradle and in fluid communication with said counter recoil cylinder, a recuperator piston and compression means in said recuperator cylinder compressively responsive to fluid pressure of said counter recoil cylinder for actuating counter recoil movement of said counter recoil piston, said recuperator piston movably cooperating with said recoil and counter recoil pistons during barrel recoil to absorb barrel recoil forces, and a fluid barrel counter recoil movement buffering system fluidly independent of said barrel recoil movement absorbing and counter recoil movement providing fluid systems, said buffering system including a buffer fluid cylinder attached to said cradle, buffer fluid in said cylinder, a movable buffer piston within said buffer cylinder and having a movable piston rod in contact with and movably responsive to recoil and counter recoil movement of said breech ring, said buffer piston movably cooperating during barrel counter recoil movement with said recoil piston to cushion said counter recoil movement of said barrel, said buffer piston having a restricted

fluid flow-permitting diameter less than the internal diameter of said buffer fluid cylinder.

2. Gun recoil movement responsive mechanism as set forth in claim 1 in which said recoil movement absorbing fluid system includes a floating fluid seal slidingly interposed between said recoil cylinder and recoil piston.

3. Gun recoil movement responsive mechanism as set forth in claim 1 wherein said compression means in said recuperator comprises a plurality of compression springs.

4. Gun recoil movement responsive mechanism as set forth in claim 1 wherein said recoil cylinder is tapered converging toward said breech ring.

5. Gun barrel recoil movement responsive mechanism for absorbing barrel recoil and for returning said barrel to battery position on a gun with a fixed cradle and a movable barrel with breech ring slidably mounted in said cradle, said mechanism comprising, in combination, a barrel recoil movement absorbing fluid system including a recoil cylinder carried by said cradle adjacent said barrel, a movable tubular recoil piston concentrically within said recoil cylinder and attached to said breech ring for recoil and counter recoil actuated movement therewith, a flange on said recoil piston in and of a diameter less than said recoil cylinder to permit restricted fluid flow therein, and a recoil force absorbing fluid within said recoil cylinder, a barrel counter recoil movement providing fluid system fluidly independent of said barrel recoil movement absorbing fluid system and including a counter recoil cylinder fixed to said cradle, a movable counter recoil piston concentrically within said counter recoil cylinder and fixed to a piston rod secured to said breech ring for actuating counter recoil movement of said breech ring upon termination of barrel recoil movement, said counter recoil piston movably cooperating with said barrel recoil piston during barrel recoil to absorb barrel recoil forces, a recuperator cylinder fixedly mounted to said cradle and adjacent to and in fluid communication with said counter recoil cylinder, a recuperator piston and compression means

within said recuperator cylinder for actuating counter recoil movement of said counter recoil piston upon termination of barrel recoil movement, and counter recoil fluid within said counter recoil cylinder responsive to recoil movement of said counter recoil piston to compress said compression means, said recuperator piston movably cooperating with said recoil and counter recoil pistons during barrel recoil to absorb barrel recoil forces, and a fluid barrel counter recoil movement buffering system fluidly independent of said barrel recoil movement absorbing and counter recoil movement providing fluid systems, said buffering system including a buffer fluid cylinder fixed to said cradle, a movable buffer piston within said buffer cylinder, and a piston rod on said buffer piston in contact with and movably responsive to recoil and counter recoil movement of said breech ring, said buffer piston movably cooperating during barrel recoil movement with said recoil piston to cushion said counter recoil movement of said barrel.

20 6. Gun recoil movement responsive mechanism as set forth in claim 5, wherein said recoil cylinder is tapered converging toward said breech ring.

7. Gun recoil movement responsive mechanism as set forth in claim 5, wherein said compression means within 25 said recuperator cylinder comprises a gas.
